M. F. DESPECHER

FLAG

Filed April 16, 1927

UNITED STATES PATENT OFFICE.

MARY FRANCES DESPECHER, OF RALSTON, NEBRASKA.

FLAG.

Application filed April 16, 1927. Serial No. 184,263.

This invention relates to flags and has for an object to provide a flag having new and improved features of construction augmenting the wearing qualities of the flag as well as presenting features which prevent the flag from sagging in a calm.

A further object of the invention is to provide a flag, the present utility of which is believed to be as a golf marker while it is to be understood that the invention is not limited to that use but includes any flag wherein the corners are turned inwardly upon opposite sides of the flag so that at the fly end of the flag it is thickened by several laminated layers of the fabric.

With these and other objects in view, the invention comprises certain novel arrangements, constructions and combinations as disclosed in the drawings together with equivalents thereof.

In the drawings:

Figure 1 is a view of the flag in side elevation showing in dotted outline the original dimensions of the flag from which the completed flag has been folded.

Figure 2 is an enlarged and exaggerated section taken on line 2—2 of Figure 1.

Figure 3 is a view of the flag in edge elevation.

Like characters of reference indicate corresponding parts throughout the several views.

It is well known that in various utilities of flags and markers, notably in the use of such devices in markers for golf courses, the flags are subjected to exceedingly hard wear and, therefore, must be replaced often. Flags ordinarily employed also fall down in a substantially straight line during a calm and do not perform their function of indicating the spot marked.

The present flag is intended to overcome these difficulties in the maximum degree by providing the fly end of the flag with reinforcements, which reinforcements are formed from parts of the flag structure itself folded, which not only reduces wear to the minimum but also serves to hold the flag more or less extended during a calm and, therefore, in position to be seen.

Initially the flag is a substantially rectangular member, the size indicated by the

dot and dash line 10. This is constructed preferably of two thicknesses of fabric, one upon each side, with the marginal edges 55 turned inwardly and secured by rows of stitching 11. Also preferably the fabrics upon the opposite sides of the flag will be of different colors, although, of course, the different coloring does not enter into the mechanical invention involved herein.

The rectangular flag thus constructed has its fly corners folded, one upon one side and one upon the other side of the body as indicated at 12 and 13. These infolded and 65 overlapping corners will be stitched to the body by means of rows of stitchings 14 which also constitute the seaming of the edges of the infolded corners, the continuations of the stitching 11.

The folds 15 produced by the infolded edges will also be maintained in close contact by means of stitches 16 whereby the flag at the fly end presents one terminal triangle 17 of merely the double thickness of the 75 fabric, but two adjacent triangles 18 which are double the thickness of the two laminæ with a quadrangle 19 presenting eight thicknesses of the fabric.

If, therefore, in the use of the device the 80 external triangle 17 should wear and disconnect itself from the balance of the flag or even the triangles 18 should wear through, there would still be a sufficient amount of the flag remaining to serve every 85 purpose.

While the means of attaching the flag to the stake forms no particular part of the present invention, it is shown as comprising a strip 20 folded over the end of the flag 90 secured by stitching 21 and provided with eyelets 22 or any approved means for attaching to the stake, which may be accompanied by and co-act with a cord or cable 23.

What I claim to be new is:

1. A flag composed of connected laminated sheets, parts of said laminated structure being folded to and secured upon opposite sides.
2. A flag composed of connected laminated sheets exposing different colors, parts of said laminated structure being folded to and secured upon opposite sides.
3. A flag comprising a body composed of

fabric having the upper and lower corners of the fly end folded toward the median line and secured in such position.

4. A flag comprising a body composed of laminated fabrics having the upper and lower corners of the fly end folded toward and over the median line and overlapping and secured in such position.

5. A flag comprising a body composed of laminated fabric having the upper and lower corners of the fly end folded toward and across the median line and overlapping and stitched into folded and overlapped position.

In testimony whereof I affix my signature.

MARY FRANCES DESPECHER.
